GAME.

Application filed August 19, 1922. Serial No. 582,841.

To all whom it may concern:

Be it known that I, ANNIE G. STEWART, a citizen of the United States of America, residing at Toledo, Lucas County, Ohio, have invented new and useful Games, of which the following is a specification.

This invention relates to games.

This invention has utility in connection with playing cards, more especially as of two series, one of direction, route or transit, and the other of location or article, as merchandise, which specifically may have supplemental interest as operated in conjunction with advertisements as shopping expeditions.

An object of the invention is to provide entertainment as well as instruction.

Referring to the drawings:

Fig. 1 is a front view of the two characters of cards in the selected series, as the direction or transit series of cards;

Fig. 2 is a front view of some typical cards of the location series, which in connection with shopping adaptation of the game may supplementally designate sales departments or merchandise, more or less specifically;

Fig. 3 is a fragmentary view of an advertisement which may be used in conjunction with shopping expedition adaptation of the game;

Fig. 4 is a back view of a transit card; and

Fig. 5 is a back view of a location or merchandise card.

The game may be developed along lines for familiarizing players with the various general departments or lines of goods of a particular retail mercantile establishment, wherein the cards may not only carry the insignia for the game, but may be a most suitable field for general advertising of the establishment. The possibilities of the game may readily be extended to whet interest in current advertisements of the establishment, and thus prove a source of amusement continually varied by the current advertisements, with points in the game going to those of quick perception and mentally alert. Accordingly, notwithstanding the cards to an extent may be played as a pure game of chance in a simple handling of the cards, there may be built therefrom educational value, not only as to the business house geography, but also sharpening of wits for quick clear action in continuously arising emergencies.

Direction, travel or transit cards may be of two kinds at least. In a department store or mercantile establishment of several floors, these cards may be for elevator transit, as up cards 1, and down cards 2. In a mode of playing the game herein, these travel cards are selected, and to make possible a maximum of agility upon the part of the player, the cards 1 may be given a safety color as yellow, and the down cards 2 a danger color as red.

The cards as regularly to be played may be fifty-two, or even more, or less. The cards of this second location series when adapted to a general dry goods establishment may include cards to designate merchandise as cards 3, 4, 5, 6.

In a simplified use of these two series of cards, the shuffled second series of cards may be dealt out, say six cards face down to each player, and to each player there is also allotted three cards 1 and two cards 2, i. e., three up cards and two down cards, being selected or known cards of the other series. Each player now has eleven cards. The player next the dealer may start the game by turning up or exposing the top card of the location series. It is assumed that the player in this shopping expedition enters on the first floor. Should the card from the location series be first floor, as card 3, it is played and left at such player's position. The next player then lays face up the top card of the location series at such player's position. If such be fifth floor, such second player must first play card 1 and over it play the location card.

Assuming a player has location cards turned up in sequence as for second, first, third and fourth floors, direction cards are used as up, down, up, up. Such player still has two location cards and but one direction card. Should the next card be for the fifth floor, this player is out of the hand because unable to get up. However, should such next card be card 6, it may be played, as on the same floor. Should the card be card 4, the last direction card 2 may be played 105 and card 4 thereover.

First game.

This game as so operated may be a pure game of chance—on the sequence of dealing, or rather receiving, the sequentially unknown location cards. The winner of a hand may be the one to have played all location cards and be on the first floor, 5 or nearest such first floor with the cards all played, or most nearly all played. In the event of tie, the one first completing the hand may be considered the winner of such hand, in the building up of points for 10 the game. This game is one which may be played by small children, able to read, thus training them in the general merchandise and how to get about a large store for special goods.

15 Second game

Added zest may be given the game by the use of an advertisement 7, say a current handbill or newspaper miscellaneous list of goods, which may or may not be priced for bargain sales. The points may be based upon the maximum number of purchases. To this end, the advertisement may be open for inspection by all the players. The one turning face up a location card is obligated to play a direction card if required. The face up location card as simultaneously exposed to all the players may be claimed for a purchase in such location by the first to announce specific article with its price or bargain interest as of the location played, such purchase to be from the advertisement. In one embodiment, the winner may be the one making the greatest number of purchases.

Third game.

As a game, matters may be further complicated for increasing educational value, 40 as well as also lending further points of chance. For shopping, a given amount may be allotted each player as a shopping purchaser. Assuming the credit be $25.00 for each player, the winner is the one most 45 nearly consuming the credit. Of course, in considering points for credit, such may or may not be included to modify in this latter case, according to the ideas of the players.

Fourth game.

With large or page newspaper advertisements from large department stores, changed daily, there is readily and economically at hand, interesting diversity in the advertisement adjunct use of this game, not only to sustain popularity of this game, but to enhance the advertising value thereof. It is to be noted that as above discussed, the fourth game is one which may include all the preceding games and played in the same way as in the preceding games. Such is true of any successive game as to the preceding game as herein explained, although to meet the emergencies of cards the players may adapt the cards or card series to other variations. 60 65

What is claimed and it is desired to secure by Letters Patent is:

1. A playing card game embodying a series of cards of location of different designations and a series of transit cards having designation for routing the player in either of two directions, whereby a player to take a played location card must from a limited hand lay down a proper direction transit card for continuity of progress from said player's location at starting or as last played to the last played location card designation in depleting such player's hand of location card as restricted by the limited hand of transit cards. 70 75 80

2. A shopping game comprising in combination with a special sales list, of a series of location cards for goods of such sales as in a merchandising establishment, and an elevator series of cards of up and down designations as supplied in a limited hand to the players, whereby a player in contesting for taking advantage of special sales must, as from such player's starting position or last played location, play an elevator card for transit to the played location card and then elect a special sale item or items under the location card as played. 95

3. A shopping game comprising establishing a given credit for each player in combination with a special sale list, of a series of location cards for goods of such sale as in a merchandising establishment, and an elevator series of up and down transit designation cards supplied as a limited hand to the player, whereby an exposed location card is claimed by the player who first announces special sale article within the domain of such location card with simultaneous playing of proper transit card for such player thereto. 100 105

In witness whereof I affix my signature.
